CLAIM

I claim the ornamental design for a leg sleeve, as shown and described.

DESCRIPTION

FIG. 1 is a perspective view of a leg sleeve, showing my new design;

FIG. 2 is a right side view thereof;

FIG. 3 is a left side view thereof;

FIG. 4 is a front view thereof;

FIG. 5 is a rear view thereof; and,

FIG. 6 is a top view thereof.

The broken lines of the leg sleeve, and the unshaded areas within the broken lines, depict portions of the leg sleeve that form no part of the claimed design.
